UNITED STATES PATENT OFFICE.

JOHN S. BRIEL AND NICOL R. BRIEL, OF BROWNSVILLE, PENNSYLVANIA.

TRACE-HITCH.

SPECIFICATION forming part of Letters Patent No. 737,068, dated August 25, 1903.

Application filed June 9, 1903. Serial No. 160,688. (No model.)

To all whom it may concern:

Be it known that we, JOHN S. BRIEL and NICOL R. BRIEL, citizens of the United States, residing at Brownsville, in the county of

5 Fayette and State of Pennsylvania, have invented a new and useful Improvement in Trace-Hitches, of which improvement the following is a specification.

This invention relates to certain new and 10 useful improvements in trace-hitches, and relates more particularly to that class of hitches which are adapted to be pivotally connected to the end of the whiffletree and form a rapid and secure connection between the said whiffletree and the trace.

The object of this invention is to provide a 15 hitch which will be simple in construction and effective in operation and will insure a strong but flexible connection between the trace and the whiffletree of the wagon.

In describing the invention in detail reference is had to the accompanying drawings, forming a part of this specification, and wherein like numerals of reference indicate 20 like parts throughout the several views, in which—

Figure 1 is a side elevation of our improved device in its connected position. Fig. 2 is a 25 sectional plan view showing the trace in position to be secured to the whiffletree. Fig. 3 is a similar view of its connected position.

In the drawings the reference-numeral 1 indicates a portion of the end of the whiffletree over which the usual metal cap 2 is 30 placed, and a screw 3, on the outer end of which a ring 4 is formed, passes through an aperture in the conical gripping-piece 5, the forward end of which is split, thereby forming two or more flexible members, such as 6 and 7.

40 The outer ends of these members have extensions 6' 7', and a shoulder 8, formed on the inside of these pieces, is adapted, when said pieces are drawn together, to secure the enlarged head 9 of the trace connection 10 in

45 position. The trace connection 10 is formed in two parts, between which the trace 11 is placed, said trace being secured therein by rivets 12. A tapering collar 14 is adapted to slide over the outer side of the parts 5 6 7, as 50 will be seen by reference to the drawings, and an annular shoulder 15, provided on the forward inner side thereof, will when the de-

vice is in its connected position, as shown in Fig. 3, engage the notch 16, formed in the parts 6 7, this being to secure said sleeve 55 against displacement by vibration.

In securing the parts in position the collar 14 is slid to the rear position, as shown in Fig. 2, the head 9 of the trace connection being placed within the parts 6 7. The collar is 60 then slid forward, and the head 9 is securely held within said parts. The extensions 6' 7' extend on either side of the trace connection, thereby preventing said trace from becoming twisted, as such connection can only turn a 65 certain distance before striking these extensions.

It will be obvious that various changes may be made in the details of construction without departing from the general spirit of our 70 invention.

Having fully described our invention, what we claim as new, and desire to secure by Letters Patent, is—

1. In a trace-hitch, the combination of a tapering bifurcated locking member, pivotally connected to the whiffletree, a tapering sleeve adapted to operate over said locking member, and a trace connection having an enlarged head adapted to be secured within said locking member when the same is in its closed position, substantially as described.

2. In a trace-hitch, the combination of a locking member the rear end of which is pivotally connected to the whiffletree, spring 85 locking-fingers formed on the forward end of said member, an annular groove cut on the forward outer side of said members, a tapering sleeve adapted to operate over said members for the purpose of drawing them together, 90 an annular projection within said sleeve adapted to engage the annular groove in the members, and a trace connection having an enlarged head adapted to be secured within said members when the same are in their 95 closed position, substantially as described.

3. In a trace-hitch, the combination of a locking member pivotally connected to the whiffletree, spring-fingers formed on the forward end of said member, a tapering sleeve 100 adapted to operate over the outer side of said fingers, a projection in said sleeve adapted to fall into the cut-away portion in said fingers, an annular enlargement formed on the inside

of said fingers, a trace connection the forward end of which is bifurcated for the insertion of the trace, an enlarged head on the rear end of said connection adapted to be held by said projection on the fingers when the same are in their closed position, and a projection on the forward end of the fingers to prevent twisting of the trace connection, substantially as described.

In testimony whereof we have hereunto signed our names in the presence of two subscribing witnesses.

JOHN S. BRIEL.
NICOL R. BRIEL.

In presence of—
F. O. HENZI,
M. C. WELSH.
